(57) **CLAIM**

The ornamental design for a viscous liquid dispenser, as shown and described.

DESCRIPTION

FIG. 1 is a perspective view of a dispenser embodying our new design;

FIG. 2 is a front view of the dispenser shown in FIG. 1;
FIG. 3 is a back view of the dispenser shown in FIG. 1;
FIG. 4 is a left side view of the dispenser shown in FIG. 1;
FIG. 5 is a right side view of the dispenser shown in FIG. 1;
FIG. 6 is a top view of the dispenser shown in FIG. 1; and,
FIG. 7 is a bottom dispensing end view of the dispenser shown in FIG. 1.

The broken lines in the drawings represent unclaimed environmental subject matter illustrating the design in use and form no part of the claim.
